AUTOMATIC KNITTING MACHINE

Raymond J. Good, Philadelphia, Pa., assignor to Fred C. Good & Sons, Inc., Philadelphia, Pa., a corporation of Pennsylvania

Filed Jan. 7, 1958, Ser. No. 707,539

4 Claims. (Cl. 66—82)

This invention relates to automatic knitting machines of the full fashion, flatbed type.

With the continued decline of the hosiery market for the small mill owner in this country, an increasing number of mill owners are converting their hosiery machines to heavier gauge machines for the knitting of outer garments such as sweaters and the like. More recently, the market for sweaters knit from heavy gauge yarns has become increasingly important, and as a result, still further modifications of the basic machine are necessary to achieve the desired result. With public demand and fashion being as fluctual as it is, machine owners hesitate to go to the expense of converting, for example, a 21 gauge machine to a 10½ gauge machine, when there is always the chance that no sooner is the conversion effected, than the market demand swings back to the higher gauge fabric. For this reason, it has been desirable to provide a modification for example of a 21 gauge machine which enables the machine to knit either 10½ or 21 gauge fabric without the usual conversion expense.

Accordingly, it is the principal object of the present invention so to modify a standard flatbed, full fashion machine that it is easily converted to knit, for example, either 10½ or 21 gauge fabric.

Other objects and advantages of the present invention will be apparent from the following description when read in conjunction with the attached sheets of drawing, in which:

Fig. 1 is a perspective view showing the arrangement of special dividers and points together with a portion of fabric which has a gauge corresponding to one-half the number of needles on the needle bar;

Fig. 2 shows in side-by-side relationship the ordinary knock-over bit, together with a special knock-over bit useful in connection with the present invention; and

Fig. 3 shows the mechanism for controlling the movement of the points in accordance with the present invention.

As will be apparent to those skilled in the art, if, for example, a 21 gauge machine is to knit 10½ gauge fabric, every other needle in each section of the machine must in some way be inactivated. One possible solution is to permanently close the beards of every other needle. A similar result could be obtained by simply substituting a blind post for every other needle. Either of these solutions, however, requires expense in connection with reconversion. In general, the objects of the present invention are achieved by utilizing a point bar with a point for every other needle. Whenever it is desired to knit the lower gauge fabric, it is only necessary to activate the point bar on each course of knitting, so that every other needle has its beard covered or closed by its corresponding point at the time in the knitting cycle that those needles would ordinarily be pulling the new course through the old loops. Other minor modifications of the sinkers and dividers and the knock-over bits are helpful in achieving the objects of the present invention, but none

2

interfere with the ease of changeover from normal to half-normal gauge.

Referring first to Fig. 1 of the drawings, for a description of the knitting action and fabric produced, it will be seen that a row of conventional spring beard needles are employed. The first apparent modification of a standard machine which will be readily recognizable in this figure, is the substitution of a special slider finger 10 for the standard dividers. Note that there is one such finger between each standard sinker 11. Note further that the shape of this special slider finger is such that while it forms a supporting surface for the larger loops formed by the action of the sinkers, it is ineffective to produce loops around the individual needles with which each is associated. As the knitting proceeds, therefore, the loops formed by the action of the sinkers surround two needles rather than one.

Fig. 2 shows the enlarged knock-over bits 20 which are also very desirable to support the larger loops formed when knitting heavy gauge yarns with a machine according to the present invention. The bit is substantially the same shape as the conventional bit 21, but is somewhat larger and particularly in the vertical dimension, so that the loops are held at a somewhat higher point on the needle shanks than would be the case with the conventional bit and located substantially beneath the special slider fingers.

Referring again to Fig. 1, a plurality of points 30 are shown, one for every other needle on the needle bar. When the machine is operating, the points 30 are caused to close the beards of the needles with which they are associated, and such closure of course, takes place at a predetermined point in the knitting cycle. Those needles which are thus covered by the points, therefore, do not knit, with the result that a heavier gauge fabric is produced substantially as shown in this figure.

Referring now to Fig. 3, those skilled in the art will readily recognize the conventional narrowing mechanism including the narrowing goose neck arm 40, the narrowing machine assembly 41, the narrowing lift arm 42, the narrowing roller arm 43 and the narrowing cam 44. Adjacent the conventional narrowing cam, there is positioned on the same cam shaft a circular cam 45, which, when in engagement with the narrowing roller arm 43, will result in no movement of the narrowing machine assembly during operation of the knitting machine. Also, on the same cam shaft and positioned adjacent the narrowing cam is a third cam 47, which will provide the necessary point motion to effect a closing of the beards of every other needle as the knitting proceeds. A conventional cam follower shifting arrangement may be used such, for example, as the one described on page 34 with reference to Fig. 56 of the 1940 edition of "The Reading" prepared by Textile Machine Works of Reading, Pennsylvania.

From the foregoing, it will be apparent that whenever the cam roller 46 is shifted to engage the cam shown at 47 in Fig. 3, the action of the points will be such as to cover the beards of alternate needles on each knitting course. In order to return to 21 gauge knitting, it is only necessary to shift the cam roller to place it in engagement with the circular cam 45 shown in Fig. 3.

What is not readily apparent even to those skilled in this art is the fact that even with the special sinkers or slider fingers 10, shown in Fig. 1, that the machine will knit a 21 gauge fabric even without the formation of loops around the particular needles which are associated with the special sinkers or sliders. Further, the use of the enlarged knock-over bits in alternate positions to the standard bits is likewise ineffective to change the character of the fabric knitted with the point bar out of operation.

It will be apparent therefore that there is herein shown and described a modification of a standard flat bed full-fashioned machine on which either full gauge or half gauge fabric may be knitted. The only conversion from one to the other which is necessary is the shifting of the cam followers in each section of the machine. For this reason, with only the expense of adapting the machine to incorporate the special features disclosed herein, the machine becomes readily convertible back and forth to knit half or full gauge fabrics.

While the applicant's preferred embodiment of the present invention has been herein shown and described, applicant claims the benefit of a full range of equivalents within the scope of the appended claims.

I claim:

1. In combination with a flat bed, full fashion knitting machine, which machine includes a needle bar, a plurality of needles carried by the needle bar, a narrowing mechanism, a cam shaft, and cam means on the cam shaft for actuating the narrowing mechanism, a plurality of knockover bits and means for actuating said knockover bits, and a plurality of sinkers and dividers and means for actuating said sinkers and dividers; a point bar supported by said narrowing mechanism, coextensive in length with said needle bar, having a plurality of points thereon equal in number to one half the number of needles, mutually spaced a distance corresponding to two needle spacings and positioned to cooperate respectively with alternate needles; additional cam means carried by said cam shaft and operative to move said point bar to cause said points to close the beards on said alternate needles during the knitting of each successive course; and means to inactivate said point bar; whereby the machine may knit selectively full or one half gauge fabric depending on the use or non-use of the point bar during the knitting cycle.

2. The combination defined by claim 1 in which alternate knockover bits are of substantially greater vertical dimensions than those adjacent said alternate knockover bits.

3. The combination defined by claim 1 in which a plurality of slider fingers are provided, one positioned between each pair of adjacent sinkers, each said slider finger having an elongated nose portion of such extent that it serves as a loop supporting member only and is

45

ineffective to form a loop around its corresponding needle.

4. In combination with a standard flat bed, full fashion knitting machine, which machine includes a needle bar, a plurality of needles carried by the needle bar, a narrowing mechanism, and a cam shaft having cams thereon for actuating the narrowing mechanism; a point bar supported by said narrowing mechanism, coextensive in length with said needle bar, having a plurality of points thereon equal in number to one half of the number of needles, mutually spaced a distance corresponding to two needle spacings and positioned to cooperate respectively with alternate needles; slider fingers, one positioned between each pair of adjacent dividers, said fingers having elongated nose portions of such extent that they serve as fabric supporting members only and are ineffective to form a loop around their corresponding needles; a plurality of knockover bits, alternate bits being of substantially greater vertical dimension than the other bits, said alternate bits being positioned to underlie respectively said slider fingers; cam means carried by said cam shaft and operative to move said point bar to cause said points to close the beards of said alternative needles during the knitting of each successive course, and means to inactivate said point bar; whereby the machine may knit selectively full or one half gauge fabric depending on the use or non-use of the point bar during the knitting cycle.
